INVENTOR.

B. McDONALD

UNITED STATES PATENT OFFICE.

BEVERLY McDONALD, OF PICTON, ONTARIO, CANADA.

FILING DEVICE.

1,106,396.

Specification of Letters Patent. Patented Aug. 11, 1914.

Application filed May 17, 1913. Serial No. 768,334.

To all whom it may concern:

Be it known that I, BEVERLY McDONALD, of the town of Picton, in the county of Prince Edward, in the Province of Ontario, 5 Canada, have invented certain new and useful Improvements in Filing Devices, of which the following is the specification.

My invention relates to improvements in filing devices, and the object of the invention is to provide a simple means for filing check slips and the like so that they can be readily and quickly gotten at, and by which the total amount of each may be easily made visible without removing the slips from the 10 file, and it consists essentially of a series of counter check slip containing pockets comprising a stiff hard back piece and a soft front piece, having a cut away portion forming one side thereof, and an indicating card having a receiving pocket integral with the back piece and extending upwardly from the upper end of such back piece, as hereinafter more particularly explained by the following specification.

25 Figure 1 is a general perspective view of my file showing a series of counter check slip pockets arranged therein. Fig. 2 is a longitudinal section through Fig. 1. Fig. 3 is a perspective detail of one of the counter 30 check slip pockets showing the indicating card withdrawn from its holding pocket.

In the drawings like letters of reference indicate corresponding parts in each figure.

A is a receptacle of any suitable form provided with a support A' of any suitable form designed to support the counter check slip pockets in an inclined position within the receptacle.

B are a series of indicating counter check 40 slip containing pockets, each pocket comprises a stiff hard back piece B' preferably formed of thin sheet metal having an upturned lip B² at its lower edge in which is inserted a soft front piece B³ of any suitable 45 material such as linen, or paper. The front piece B³ is preferably cut away in an inclined direction from its lower right hand corner as clearly shown in Fig. 3 thereby clearly exhibiting the upper right hand corner of a counter check slip 1. The counter

check slips are ordinary counter check slips arranged in any suitable way and provided at their right hand corner with a space 2 for containing the amount to date, or in other 55 words, the total amount owing by the customer after the bill indicated by the corre-

sponding counter check slip has been totaled up.

B⁴ is an upward extension of the back piece B' provided with a turned over lip B⁵ and lips B⁶ and B⁷ stamped up at each lower corner of such extension piece.

C is an indicating card designed to be held in the pocket formed by the lips B⁵, B⁶, B⁷, as indicated by dotted lines in Fig. 3. I have shown three of these indicating pockets in Fig. 1, namely, pockets indicating A, B, C. Between these pockets are supplementary pockets E similar in form to the pockets above described and having indicating cards D on which is written the name of the customer. All the customers' names beginning with A are arranged behind the indicating pocket containing the letter A, and the customers' names beginning with B are arranged behind the indicating pocket containing the letter B, and so on throughout the alphabet. The pocket containers having indicating cards, having the customers' names written thereon are used for long standing accounts. The pockets formed on the indicating containers may be utilized to contain petty or transitory accounts. It will readily be understood from this description that when the merchant desires to refer to any account, he may readily place his fingers upon the pocket containing such account, and withdraw it from the file. If he merely wishes to find out the amount owing by any customer, he simply raises the corresponding pocket until the total amount indicated at 2 (see Fig. 3) appears above the remaining pockets. He can then carry over such amount to the next check slip if desired or refer such amount to the customer. To hold the pockets in place I preferably provide a spring 3 bearing against the front pocket so as to hold the pockets together.

What I claim as my invention is:

1. In a filing device, a check slip container comprising a stiff back piece and a front piece formed of pliable material attached at the bottom to the back piece and having a cut away portion on one side thereof, as and for the purpose specified.

2. In a filing device a receptacle, a series of check slip containers comprising a stiff back piece and a pliable front piece and a visible portion bearing an indicating letter and a series of intermediate pockets also formed with a stiff back piece and a pliable

front piece and visibly bearing the customer's name, as and for the purpose specified.

3. In a filing device, a check slip container comprising a sheet metal back piece having an upturned lip at its lower edge and a flexible front piece secured in the lip and cut away at one side from the bottom in an inclined direction, as and for the purpose specified.

4. In a filing device a check slip container comprising a sheet metal back piece having an upwardly extending portion having an

overturned lip at its upper end and forwardly stamped lips in proximity to its lower corners and designed to receive an indicating card and a front piece formed of pliable material attached at the bottom to said back piece and having a portion cut away from one side thereof, as and for the purpose specified.

BEVERLY McDONALD.
